UNITED STATES PATENT OFFICE.

GEORGE E. NEUBERTH, OF NEWARK, NEW JERSEY.

MACHINE FOR BENDING TUBING.

1,320,338.

Specification of Letters Patent. Patented Oct. 28, 1919.

Application filed February 26, 1919. Serial No. 279,229.

To all whom it may concern:

Be it known that I, GEORGE E. NEUBERTH, a citizen of the United States, and a resident of Newark, county of Essex, and 5 State of New Jersey, have invented certain new and useful Improvements in Machines for Bending Tubing, of which the following is a specification.

This invention relates to an improved machine for bending tubes, and it is particularly adapted for bending tapered tubes. Tapered tubes have required an expensive and slow procedure when being bent, and it has therefore been customary to make 15 bent tapered tubes of two pieces and then fasten these face to face to make the complete tube.

This invention is adapted to so manipulate a straight tube that the tube is bent, and when the bending is finished the tube is smooth on the inside and the exterior is also smooth. Such bent tapered tubes as are employed for the sound boxes of talking machines are good examples of the articles made by this machine, and for the purpose of this specification I will describe the machine as one adapted to make such bent tubes, although other forms and kinds of tubes can be bent in this machine, 30 and such alterations and changing as would adapt the machine to such modifications are well within the scope of the invention.

The invention is illustrated in the accompanying drawings, in which Figure 1 is 35 a front view of the machine, and Fig. 2 is a side view. Fig. 3 is a front view of a mandrel or burnishing tool used in the machine. Fig. 4 is a top view, broken away at places to fully illustrate the position of 40 the parts when the bending operation begins, and Fig. 5 is a similar view showing the position of the parts when the bending has been completed. Fig. 6 is a side view of the machine with the parts in the position 45 shown in Fig. 5. Fig. 7 is a detail perspective view of the front end of the mandrel, and Fig. 8 is a detail view showing a modified form of burnishing tool.

The machine can be mounted on any suitable support or standard 10 and is best placed about waist high to the operator. On the support rests the base 11 of the machine, which has a boss 12 on one side and a block 13 on the other side. A die consisting of two members is mounted on the base 10, one member 14 swinging on a

spindle 15 in the boss 12, and a sliding member 16 resting against the block 13. The swinging die member 14 and the sliding die member 16 are preferably worked in unison, 60 and to provide for this the swinging member 14 is secured by screws 17 to the pinion 18, which pinion is in mesh with the rack 19 to which the sliding die member 16 is fastened by the screws 20. The member 14 is 65 provided with a cap piece 21 which swings with it, this being provided for by a key 22, and a depending flange 23 has a handle 23^a secured thereto, by means of which an operator can move the dies to any desired 70 position.

The dies are recessed to receive a tube. In the form shown they are recessed to receive a tapered tube 24, which has an off-set portion 25 on its large end. The swinging die has a filler block 26 which fits against the flange 23 of the cap piece 21 and is recessed to receive the large end of the tapered tube, this filler block being alined with the sliding die when the dies are in 80 what might be termed their closed positions, and is adapted to be removed to permit the removal of the tube after it is bent. A suitable cap 27 is fastened by suitable means, such as screws 28, to the block 13, and the 85 movable die 16 is thus held in position when it slides, and thus relieving the rack 19 of strain and consequent binding in its sliding movement.

On the rear end of the base 11 is secured 90 a bracket 29 which supports a bearing 30 in which a sleeve 31 is rotatably mounted, the sleeve being adapted to be rotated by suitable means such as a pulley 32, which is driven by belting. A shaft 33 is arranged 95 inside the sleeve 31 and is rotatable therewith, being provided with a key or feather 34 which insures the simultaneous rotation of the sleeve and the shaft. The forward end of the shaft 33 forms a mandrel and 100 is illustrated in detail in Figs. 2, 3 and 7, the forward end being channeled, as at 35, leaving a central web 36 which is calculated to strengthen the mandrel, and the forward ends of the channels are cut away to form 105 inclined or beveled faces 37. The sleeve 31 has a flange 38, and cheek pieces 39 are also provided. These cheek pieces have levers 40, these being preferably secured to the cheek pieces by means of the pivotal pins 41 110 and being held in normal position by light springs 42 received in recesses in the ends

of the right-angled parts 43 of the levers and bearing against the flange 38, and thus normally holding the inclined or beveled front inner edges 49 of the levers 40 in engagement with the faces 37 of the mandrel, the outer faces of the levers at their ends being formed, as at 50, into surfaces that are adapted to burnish or smooth metal when placed in sliding contact therewith.

If desired, the modification shown in Fig. 8 can be employed, in which the lever 40 is shown as being provided with an additional burnishing surface 51, the additional surface being adapted to do the preliminary burnishing or spinning, as will be herein-after described. The rear end of the shaft 33 is screw-threaded, as at 52, having suitable nuts 53 and preferably a thrust bearing 54 which bears against one end 55 of a lever 56, which is attached at 57 to an arm 58 and is pivoted, at its extremity 59, to a bar 60 which is connected to a bar 61 by a turnbuckle 62, the bar 61 being pivotally connected as at 63, to a short arm 64 swinging on a pivot 65, to which pivot is attached a finger 66, this being preferably fastened to the pivot 65 by means of a square post and recess, the end 67 of the finger engaging a stud 68 on the sliding die 16.

The operation of the machine is as follows:

The swinging die is moved to the position shown in Figs. 1 and 4, but the turnbuckle 62 is turned so that the shaft 33 is moved forward, and this permits the light springs 42 to push the ends of the lever 40 inward, and the lever and the burnishing tools 50 are substantially flush with the outside end of the mandrel, and the small end of the tube 24 can pass over the mandrel and assume the position shown in Fig. 4. The turnbuckle 62 is then turned to pull the shaft 33 backward, and the inclined faces 37 acting on the inclined faces 49 force the studs or ends 50 of the burnishing tool to be in contact with the inner face of the tube to be bent, this position being clearly illustrated in Fig. 4. The machine being in operation, the pulley 32 is revolving at a rapid rate, carrying with it the sleeve 31, the shaft 33 and the burnishing tools 50, and the operator now moves the handle 23^a so as to pull the tube 24 endwise by means of the swinging die member 14, which has the filler block inserted in it, but the tube has a tendency to wrinkle on the wall being bent around the smallest radius, and the rotating burnishing tool smooths these wrinkles out. Until such wrinkles are smoothed, the swinging die is halted in its swinging movement, as any wrinkles will obstruct the forward movement of the die 16 and its stud 68 will not permit the finger 66 to move, and this finger 66, being connected, by means of the arm 64 and the bars 60 and 61, the turnbuckle 62

and the lever 56, to the shaft 33, holds the shaft so that the inclined faces 49 of the levers 40 can not push the shaft 33 forward. Such pushing forward of the shaft is only possible when the die 16 can slide forward, and the die can only go forward when the wrinkles have been removed from the metal in the tube that is being bent. This insures a smooth product when the bending is complete, it burnishes the inside of the tube, it regulates the swinging of the handle 23^a and provides a good operation that insures a satisfactory result.

As the handle 23^a is swung, the swinging die member rotates through a partial rotation and the die member 16 moves tangentially thereto, and when the bending has been completed the filler block and the tube are quickly loosened, the filler block is taken out and the bent tube can be removed through the back end of the swinging die member, the swinging die member is again returned to the position shown in Fig. 1, the filler block again inserted and the machine is ready for another operation as above described.

It will be understood that various forms of tubes can be bent in this type of machine, and that changes can be made in the details of the machine without departing from the scope of this invention as defined in the claims.

I claim:

1. A machine for bending tubes comprising a die to receive a tapered tube, means for moving the die to bend the tube, an expansible and contractible mandrel, and means for yieldingly holding the mandrel against the tube.

2. A machine for bending tubes comprising dies to receive a tube and adapted to move the tube in an arc, an expansible mandrel in the tube, means for yieldingly holding the mandrel against the tube, the dies and the mandrel being rotative relative to one another.

3. A machine for bending tapered tubing comprising a die to pull the tube endwise into a bent form, and a revolving burnishing tool bearing on the inside of the tube at the place of bending.

4. A machine for bending tapered tubing comprising a die adapted to swing and thus pull a tube endwise into a bent form, a rotating contractible burnishing tool in said tube and arranged so that it operates against the inside of the tube at the point where the bending takes place, and means for actuating the tool so that it contracts toward the small end of the tube so as to exert equal pressure throughout the length of the bent portion.

5. A machine for bending tubing comprising a die made of two members, the members being adapted to embrace a tube,

- one of said members being mounted to swing and pull the tube endwise into a bent form, a burnishing tool operating on the inside of the tube where the bending takes place, 5 means for releasing and increasing the pressure exerted by the tool, and an operative connection between the die and said means whereby the progress of the die regulates the pressure.
- 10 6. A machine for bending tapered tubes comprising a die having a swinging member and a member sliding tangentially thereto, the members being recessed to receive a tapered tube, a mandrel rotating within the 15 recess opposite the point where the members of the die separate, a burnishing tool on the mandrel, means for moving said tool against the inside of a tube in said die, and means for holding the tool against the tube 20 as the tube is moved with its large end first.
7. A machine for bending tapered tubes comprising a die formed of a swinging member and a member sliding tangentially thereto, said members being recessed to receive a tapered tube, a burnishing tool rotatably arranged within the tube, means for holding the tool against the inside of the 25 tube, and means connecting the die with the holding means to cause the tool to yield only 30 as the die progresses.
8. A machine for bending tapered tubes comprising a die having a swinging member with a curved recess to receive and bend a tapered tube, a sliding die with a tapered 35 recess to receive a straight tapered tube, means for causing the dies to move in unison, a burnishing tool bearing on the inside of the tapered tube, and means controlled by the progress of the die for regulating the 40 pressure of the tool against the tube.
9. A machine for bending tapered tubes comprising a die having a swinging member with a curved recess to receive and bend a tapered tube, a sliding die with a tapered 45 recess to receive a straight tapered tube, means for causing the dies to move in unison, a burnishing tool, means for causing the burnishing parts of the tool to be expanded and contracted, and means connected to and controlled by the die for regulating such expansion and contraction means.
- 50 10. A machine for bending tubes comprising a die to receive a tube and pull it endwise into a bent form, a mandrel having 55 a recess therein, the end wall of the recess being inclined, and a lever in the recess with

an inclined end bearing on the inclined wall, the lever and the mandrel being slidable longitudinally relative to each other.

11. A machine for bending tubes comprising a die to receive a tube and pull it endwise into a bent form, a mandrel having a recess therein, the end wall of the recess being inclined, a lever in the recess with an inclined end bearing on the inclined wall, the lever and the mandrel being slidable longitudinally relative to each other, and means connected to and controlled by the die for causing such relative sliding movement.

12. A machine for bending metal tubes comprising a die having two members, a swinging member and a sliding member, the sliding member moving tangentially to the swinging member, both members being recessed to receive a tube, means for moving the swinging member so as to pull the tube endwise into a bent form, a mandrel adapted to slide and to rotate within the tube, the mandrel having a recess, a lever resting in the recess and held against sliding movement, but adapted to rotate with the mandrel, the lever having a burnishing part thereon, the lever and the mandrel having co-acting means for moving the end of the lever radially when the mandrel is slid horizontally, manually operated means for sliding the mandrel, and means connected with and controlled by the die for permitting the sliding of the mandrel.

13. In a tube bending machine, a mandrel having a projecting burnishing part, means for moving a metal element to be treated along said burnishing part, said element being adapted to move the burnishing part in one direction, and means controlled by the element moving means for moving the burnishing part in the opposite direction.

14. A machine for changing the conformation of metal tubing comprising a die having a recess to receive the tubing, said recess being shaped to define the finished product, and a burnishing tool rotatably mounted in said tube and adapted to bear on the inner surface of the tube, said die and burnishing tool being movable longitudinally relative to each other.

In testimony that I claim the foregoing, I have hereto set my hand, this 25th day of February, 1919.

GEORGE E. NEUBERTH.
